CLAIM

The ornamental design for an electronic device mount, as shown and described.

DESCRIPTION

FIG. 1 is a front, right, top perspective view of an electronic device mount;

FIG. 2 is a back, left, bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device mount that form no part of the claimed design. The dot-dashed broken lines represent boundaries of the claimed electronic device mount and form no part of the claimed design.
